UNITED STATES PATENT OFFICE

ROBERT ROSCOE, OF CLARENDON HILLS, ILLINOIS, ASSIGNOR TO WESTERN ELECTRIC COMPANY, INCORPORATED, OF NEW YORK, N. Y., A CORPORATION OF NEW YORK

HEAT-TREATING APPARATUS

Application filed September 30, 1925. Serial No. 59,577.

This invention relates to heat treating apparatus and more particularly to apparatus for inserting and withdrawing materials to be heat treated.

5 The object of the invention is to provide simplified and improved apparatus for heat treating material whereby the material may be conveniently and expeditiously handled with a minimum of manual labor prior to, 10 during and subsequent to the treatment thereof.

The invention is directed principally to improvements in apparatus for treating ferrous articles by a process described in the 15 co-pending application of F. B. Rinck, Serial No. 744,291, filed October 17, 1924.

In accordance with the main features of the invention in one embodiment thereof, the apparatus comprises an improved furnace, a charger therefor and means for supporting the material being treated. The furnace is provided with an air tight cylindrical muffle having a cradle for receiving a frame containing the material and supporting it 25 above the bottom of the muffle. A steam superheater comprising a plurality of interconnected lengths of pipe, the length farthest away from the point of intake of the steam being provided with steam discharge 30 ports, preferably nickel-copper alloy, is positioned entirely within the muffle. The charger includes a transversely moving car and a charging arm or boom adapted to be moved longitudinally thereof. The charging arm is mounted upon a plurality of rollers, one of which functions to advance or 35 retract the arm, while another may be elevated to produce a vertical movement of the arm around a pivot associated with the driving roller.

40 Other objects and features of the invention will be more readily understood from a consideration of the following description taken with the accompanying drawings, in which

45 Fig. 1 is a view in perspective of a double furnace and associated charging and storage apparatus embodying the features of the present invention; the arm or boom of the

charger being shown in an intermediate position;

50 Fig. 2 is a perspective view of the muffle portion of the furnace illustrating features thereof including a steam superheater and the cradle for supporting material therein, the position of the electrical heating elements therefor being indicated schematically;

55 Fig. 3 is an enlarged sectional view of a portion of the superheater shown in Fig. 2;

Fig. 4 is a fragmentary plan view of the superheater;

60 Fig. 5 is an end view of the charging mechanism with the charging arm in an advanced position, a part of the view being broken away to more clearly show features thereof;

65 Fig. 6 is a side elevational view of the mechanism shown in Fig. 5, part of the view being broken away to more clearly illustrate the construction thereof;

70 Fig. 7 is a plan view of the same mechanism, parts of the view being broken away to more clearly illustrate features thereof;

75 Fig. 8 is a sectional view taken on the line 8—8 of Fig. 7 looking in the direction of the arrows;

80 Fig. 9 is an enlarged view of a portion of a device for supporting articles to be treated within the furnace, and

Fig. 10 illustrates another form which the supporting device may take where a differently shaped article is to be treated.

85 Referring now to the drawings in which like numerals are employed to designate similar members throughout the several views, and more particularly to Fig. 1, the numerals 10 and 11 refer generally to the left and right hand units of a bank of furnaces. A charger generally designated by the numeral 12 is adapted to travel on parallel floor rails 13 for the purpose of handling racks generally designated by the numeral 14 for holding material to be treated 90 within the furnace. A cooling shed 15 houses a plurality of trucks 16—16 which are adapted to support the racks when such racks are handled during the loading or other preparation thereof prior to their insertion 95 into the furnaces. A cooling shed 15 houses a plurality of trucks 16—16 which are adapted to support the racks when such racks are handled during the loading or other preparation thereof prior to their insertion 100

into the furnace or during the cooling of the material after removal from the furnace.

As shown in Fig. 1 a pair of furnace units are arranged one next to the other, but in order to simplify the description they will be described as though they were single units. The furnace proper may be of any usual construction having the usual frame and usual heat insulating walls (not shown in detail in the present drawings because the invention does not relate thereto). One of the features of the furnace is the muffle thereof, which is shown in Fig. 2 and indicated by the numeral 20. A pair of ridges 21 extending the full length of the muffle and a pair of apertured bracket members 22 corresponding in length co-operate to form a cradle on which a rack of material 14 is adapted to be supported. An annular recess in the end of the muffle is designed to hold suitable packing, such as an asbestos packing ring 27.

Within the muffle is a superheater 23 shown in section in Fig. 3 and in full in Fig. 4 which is a plan view thereof. The superheater 23 is adapted to receive steam through a pipe 24 from a source of supply (not shown), the pipe 24 being branched at 25 to form oppositely disposed pipe sections 30 in each of which are placed a plurality of inserts 26 (Figs. 3 and 4). These inserts are for the purpose of discharging dry steam into the muffle of the furnace and are preferably formed of a nickel-copper alloy so that they will not be readily oxidized by the conditions which prevail within the furnace during the normal use thereof.

Referring again to Fig. 1, the muffle, being integrally closed at its rear end, is provided at its front end with a door 30. The door is held in engagement with the muffle by means of cross-arms 31, which are held in position by bolts 33-33 extending through suitable lugs on the door and the end wall of the furnace, and screws 32 threaded in the arms 31 and adapted to have their ends engage suitable portions of the door 30. The face of the door 30 being accurately machined, forcing it against the asbestos packing ring 27 produces a practically air tight seal of the muffle which is essential in a furnace of this type. Suitable means, such as an air actuated mechanism indicated at 35, is provided to facilitate raising of the door 30 for the purpose of charging or removing the treated material from the muffle as shown in Fig. 1. As shown in Fig. 2, electrical heating elements 36 of any suitable type are placed some distance away from the muffle in order to obtain an even heat through the muffle wall.

Referring now to Figs. 5, 6, 7 and 8, the charger generally designated in Fig. 1 by the numeral 12, comprises a main frame 40 having a plurality of wheels 41 secured

thereto, by means of which the charger is moved along the rails 13. The wheels 41 on one side of the charger have integral therewith sprocket gears 42 meshing with chains 43 which also mesh with gears 44 on a shaft 46 carrying an integral beveled gear 45. A beveled pinion 47 meshing with the gear 45 may be turned by means of a hand wheel 48 to propel the car by means of the mechanism described. The hand wheel 48, together with the beveled pinion 47, is adapted to be withdrawn to the position shown by the dotted lines in Fig. 5, and may be retained in that position by suitable means such as a lever 49 which acts frictionally upon the pinion shaft, to permit the charger to be moved by hand without interference from the advancing mechanism. A construction identical with that described, is provided on the opposite side of the charger to permit operation from either side thereof, the hand wheel associated with this duplicate structure being indicated by the numeral 50 (Figs. 5 and 7). The charger is provided with a charging arm or boom 55 comprising a plurality of parallel I beams suitably attached to but spaced from each other, supported by rollers 56 and 57 and guided by an upper retaining roller 58. The arm is moved longitudinally upon the rollers by means of hand wheels 60 and 61, which are both mounted upon a shaft 62 having pinned thereto a pinion 63 which meshes with a recessed geared portion 65 upon the roller 56, a similar recessed geared portion 66 being also provided, and the two gears meshing with a pair of racks 70 which are integral with the charging arm 55.

The charging arm elevating mechanism comprises a pair of hand wheels 90 and 91 integral with a shaft 92 having keyed thereto pinions 93 and 94. As indicated in Figs. 7 and 8 duplicate elevating mechanism is provided on either side of the charger, but in order to simplify the description the mechanism associated with hand wheel 91 (Fig. 7) will be described in detail. The pinion 94 meshes with a gear 95 on a shaft 96 carrying integral therewith a smaller pinion 97. The pinion 97 meshes with a geared portion 100 of an eccentric member 101 (Fig. 8). The gear 100 rotates about an axis which coincides with the center point or axis of a ball bearing 102 suitably supported in the main frame of the charger. A shaft 105 supporting the roller 57 is positioned eccentrically in the member 101 and is carried about the axis of the gear 100 when this member is rotated, thereby either raising or lowering the shaft 105 and obviously the roller 57 as well. This causes an elevation of the front portion of the charging arm as shown by the dotted lines in Fig. 6 about an axis which is between the rollers 56 and 58. By this means the charging arm

when positioned under a rack of material may be elevated in the manner described and again lowered to deposit the rack in a new position. When employing the charger the truck 16 having an open upper portion designed to permit the insertion of the charging arm in order to raise the rack of material is very desirable.

In order to assist in the handling of material being treated by the process previously mentioned hereinbefore, an improved material or article holding rack is provided. This rack, shown in perspective in Fig. 1, is provided with a base 110 in which are inserted (Figs. 9 and 10) suitable uprights 111. The hollow parts to be treated, such as the base and upright portions of telephone desk stands, designated by the numerals 112 and 113, respectively, are placed upon the uprights 111, suitable spacing members 115 or 116 having apertures therein being placed therebetween. These spacing members keep the parts separated so that no surfaces or adjacent articles will touch and thus insure the proper treatment of all surfaces, the holes therein permitting free circulation of the gases in the muffle, which circulation is necessary if the best results are to be obtained in the practice of the method referred to above.

In the operation of the furnace the parts 112 or 113 are mounted upon the rack 14 which has been preliminarily placed upon one of the trucks 16. The charger 12 is then brought to a position in front of the filled truck by the operation of the hand wheel 48 or 50, and accurately aligned so that the charging arm may be advanced by means of the hand wheel 60 or 61 between the uprights of the truck 16. The arm is then elevated by rotating the hand wheel 90 or 91 to raise the rack from the truck, and while in an elevated position it is retracted by means of the hand wheel 60 or 61. The charger is then moved into position in front of the muffle of the furnace by operating the hand wheel, the door thereof is opened and the arm advanced into the furnace. The rack of material is then lowered into position upon the members 22 by the lowering of the arm by the hand wheel 90 or 91. The charging arm is then withdrawn by the operation of the hand wheel 60 or 61 and the muffle closed by the door 30, the arms 31 placed in position across the face of the door and secured with the bolts 33 and the screws 32 actuated to force the door against the asbestos ring 27 and sealing the muffle. The parts inserted may then be treated in accordance with the method described in the pending application referred to above, which process consists in admitting a small amount of steam into the heated muffle and simultaneously increasing the amount of steam admitted and the temperature of the muffle.

Subsequently the accumulated hydrogen and other gases in the furnace are expelled by opening the muffle door and a small amount of hydro-carbon oil is inserted in the muffle to burn out the excess uncombined oxygen. After the parts have been completely finished or treated, the rack on which they are supported is withdrawn from the muffle by means of the charging arm in a manner similar to that described for its insertion and placed on one of the trucks within the shed 15 for the purpose of cooling.

It is obvious that the invention is not to be limited by the specific embodiments shown and described, but is to be limited only by the scope of the appended claims.

What is claimed is:

1. Apparatus for handling materials to be treated, comprising a wheeled carriage, a material carrying member supported solely by the carriage designed to be extended into a treating device for charging or unloading the same, a plurality of anti-friction elements associated with the charging member, and means including one of said anti-friction elements for extending or retracting the charging member through a driving portion of the anti-friction element.

2. Apparatus for handling materials to be treated, comprising a traveling wheeled carriage, a member designed to be extended into a furnace for charging or unloading the same, a plurality of anti-friction elements associated with the charging member, means including one of the anti-friction elements for retracting the charging member through a pinion portion of one of the anti-friction elements, and means including another of the anti-friction elements for elevating the charging member to lift the materials.

3. Apparatus for handling materials to be treated, comprising a carriage adapted to be moved transversely of a treating device, an antifriction member having pinion portions, a plurality of charging members supported by the antifriction member, a retaining means positioned directly above the antifriction member, a plurality of elements for separating the charging members and having rack portions meshing with the pinion portions, and means for rotating the antifriction member whereby the charging members are actuated and the driving pinions are relieved of the weight of the charging members at all times, and means for moving the charging members carrying the materials through a predetermined angle.

4. Apparatus for handling materials to be treated, comprising a carriage, a plurality of charging members, a plurality of racks for separating the charging members, an antifriction member for supporting the charging members and having pinion portions meshing with the racks, a retaining

means positioned above the antifriction member, a roller supporting the charging members, an eccentric mechanism operatively associated therewith, means for actuating the eccentric mechanism to elevate the charging members, and means for propelling the carriage.

5. Apparatus for handling materials to be treated, comprising a wheeled carriage, 10 a plurality of charging arms, a plurality of racks for separating the charging arms, an anti-friction member for supporting the charging arms and having pinion portions meshing with the racks, a roller mounted in a fixed position directly above the anti-friction member, a movable roller supporting the charging arms, an eccentric gear operatively associated therewith, means for rotating the gear to elevate the movable roller and the charging arms, and means positioned on both sides of the carriage for effecting the propelling thereof.

6. Apparatus for handling materials to be treated, comprising a movable carriage, 25 a material carrying member mounted thereon adapted to be extended into a treating device for charging or unloading the same, a plurality of anti-friction elements operatively associated with the charging member, means integral with one of said anti-friction elements for moving the member longitudinally, and means for moving the axis of rotation of another of the anti-friction elements in an arcuate path to elevate the member.

In witness whereof, I hereunto subscribe my name this 17th day of September A. D., 1925.

ROBERT ROSCOE.
